FLATIRON REST

Thomas Jerome O'Connor, Charleston, W. Va.

Application November 11, 1941, Serial No. 418,627

15 Claims. (Cl. 38—79)

My invention relates to flat irons and more particularly to an improved rest arrangement for flat irons and the like.

Heretofore, it has been suggested to provide rest devices for pressing irons whereby, when the iron is not in use, its ironing surface is supported away from and in spaced relationship with respect to the surface of the ironing board or table. It has been proposed, for example, to attach a bracket at the side or rear of the iron in the vicinity of the handle, designed to support the ironing surface out of contact with the surface of the ironing board, when the iron is turned to rest position. It has also been proposed to use retractable rest devices, mounted upon the body portion of the iron, constructed and arranged to raise the iron so that its ironing surface is clear of the board.

While the prior art arrangements no doubt function satisfactorily for their intended purposes, they are open to certain objections which are inherent in their construction. Pressing irons equipped with rest devices in the form of a stationary bracket or other support member attached to the side or end portions of the iron, are awkward to handle for the reason that the rest obstructs the operator's view of the surface to be pressed and they further require that the iron be lifted slightly before it can be turned to the rest position. Irons having a retractable rest arrangement usually require some modification of the ironing surface to accommodate the rests when they are in the retracted position. The operator is required to manipulate a button, trigger, or other element to release the rests and force must be exerted upon the iron by the operator, in order to return the rests to the retracted position.

After considerable research and experimentation, I have developed an improved rest device for pressing irons, which overcomes the deficiency of the prior art devices referred to above, and one that possesses several advantages not found in the heretofore suggested flat iron rest arrangements, of which I am aware. In accordance with the present invention, the rest device comprises a gravity actuated support arm, normally positioned within the body of the iron, and adapted to project outwardly therefrom and support the ironing surface clear of the surface of the ironing board, when the iron is rolled or turned on its side to the rest position.

An object of my invention is to provide an improved rest device for flat irons and the like.

Another object of my invention is to provide a rest arrangement for flat irons, designed to per-

mit free and unobstructive view of the surface to be pressed, when the iron is in use.

Yet another object of my invention is to provide an improved flat iron rest adapted to support the ironing surface of the iron away from and in spaced relation with respect to the surface of the ironing board, when the iron is not in use.

Still another object of my invention is to provide a rest device for flat irons and the like, wherein the rest is automatically brought into operative supporting position when the iron is rolled or turned on its side.

A further object of my invention is to provide a rest device adapted for use with conventional types of flat irons, which is strong and sturdy in construction, consisting of but few parts and not liable to get out of order, even after long and continued use.

With these and other objects in view, which may be incident to my improvements, the invention consists in the parts and combinations to be hereinafter set forth and claimed, with the understanding that the several necessary elements, comprising my invention, may be varied in construction, proportions and arrangement, without departing from the spirit and scope of the appended claims.

In order to make my invention more clearly understood, I have shown in the accompanying drawings means for carrying the same into practical effect, without limiting the improvements in their useful applications to the particular constructions, which for the purpose of explanation, have been made the subject of illustration.

35 In the drawings:

Figure 1 is a rear view of a flat iron, with parts broken away, showing the rest arrangement of the present invention, associated with the iron.

Fig. 2 is a perspective view of a portion of the iron shown in Fig. 1.

Fig. 3 is a view similar to Fig. 1, showing the iron when tilted to a position intermediate the work and rest portions.

Fig. 4 is a view similar to Fig. 1, showing the iron in the rest position; and

Fig. 5 is a plan view, partly in section, showing the interior of the iron.

Referring to the drawings, and more particularly to Fig. 1, there is shown a pressing iron or flat iron comprising a body portion designated generally by numeral 1, having a base or sole plate 2, formed with an ironing surface 3. A cover member 4, adapted to seat on the base 2, encloses the body of the iron and also forms a support for a handle 5. The handle is attached to a suitable

bracket 6, having legs 7 and 8 at the front and rear of the iron, the bracket and cover being clamped in operative position by means of a bolt 9 threadable into the base or other part of the body portion of the iron. A heating element 10, as shown, is mounted within a recess formed in the sole plate, however, it will be understood that the heating unit may be formed integral with the plate or otherwise attached thereto in accordance with conventional practice. A weight member 11 (Fig. 5), forming the body portion of the iron, is of substantially the same configuration as the sole plate and may be held in position thereon by the bolts 9 or other fastening means.

The improved rest arrangement of the present invention comprises a weight or pendulum member 12, swingably supported on a plate or bracket 13 adapted to seat in a recess formed in the body portion 11, the pendulum being pivotally mounted upon the bracket for free swinging movement under the influence of gravity, by means of a pin 14 extending through the arms 15 and 16 (Fig. 5) of the bracket. It will be noted that the peripheral edge 17 of member 12 is cut away to form a recessed portion 18, and that adjacent this member in spaced relation thereto, there is provided a freely swingable pawl 19 pivotally mounted on bracket 13 by means of a pin 20. The purpose of this arrangement is to provide a stop device to maintain the pendulum in fixed position or release the same under certain conditions, as will be explained more fully hereinafter.

Reference again being had to Fig. 1, it will be noted that the lower end portion of pendulum member 12 is recessed or bifurcated to receive one end of a rest arm 21, pivotally attached to the pendulum by means of a pin 22. The free end of the rest arm extends through an opening formed in one side of the housing 4, and is provided with a surface contacting member 23 in the form of an enlarged button of sufficient area to provide a firm rest or support for member 21, when this member is in extended position, and also to cover the opening in the side of the iron. A suitable guide and bearing member 24, which may be in the form of a square or an annular ring, is mounted interiorly of the housing adjacent the opening through which the free end of arm 21 projects. Member 24 functions as a combined guide and bearing member, that is to say, it serves as a guide to direct arm 21 outwardly at the desired angle and it also serves as a support for the arm when it is in the retracted or extended position.

In connection with the arrangement of the rest arm and guide ring, it will be noted that arm 21 is inclined upwardly from the horizontal in the vicinity of its free end and that the inner peripheral edge 25 of guide ring 24 is formed with a curvature such that it permits the arm to move transversely of the opening in tangential relation with the inner periphery of the annulus. The purpose of this arrangement is to initially direct the arm outwardly and upwardly so that button 23 moves in a path in a direction away from the underlying surface when the iron is tilted from the work position.

Referring to Fig. 2, the handle member 5, which may be formed from wood or plastic material, is provided with a thumb rest 26, at the forward end thereof, edge 27 of the rest projecting outwardly from the surface of the handle. The rear portion of the handle is also provided with a rest 28, adapted to support the heel portion of the

operator's hand, edge 29 of the rest extending outwardly from the handle a distance substantially equal to the width of the thumb rest.

In the operation of the device, when the iron is in the work position as shown in Fig. 1, pendulum 12 assumes an approximately vertical position, with end portion of the pawl 19 resting against the peripheral edge 17 of the pendulum, arm member 21 in the retracted position interiorly of the iron housing, and button 23 drawn inwardly in the vicinity of the exterior surface of the housing 4. When it is desired to place the iron in the rest position, it is merely necessary to tilt or roll it by means of handle 5 so that it assumes the position shown in Fig. 4. In the rest position of the iron, arm 21 is projected or extended through the housing with button 23 in contact with the underlying surface 30, through the medium of pendulum 12. After the arm has been fully extended to the position shown, the free end of pawl member 19 is seated in the recessed portion 18 of the peripheral edge of the pendulum, thereby preventing inward movement of the pendulum and arm 21. Thumb rest 26, and the rest provided for the heel portion of the operator's hand, not shown, also contact with the underlying surface to provide a three-point support for the iron with the ironing surface 3, raised out of contact with and in spaced relation to the underlying surface. It will be particularly noted that the rests formed on the handle member 5 are of sufficient length to elevate the handle from the underlying surface, when the iron is in the rest position, so that the operator can conveniently grasp the handle when the iron is to be turned to work position.

In the reverse movement of the iron to return it to work position the elements operate in a reverse manner, that is to say, during the initial movement of the iron in a clockwise direction from its position as shown in Fig. 4, pawl member 19 is designed to move away from the recess ahead of or prior to movement of pendulum 12, thus releasing the pendulum so that it can move inwardly and withdraw the rest arm 21 to the retracted position. The relative position of the pawl and weight, during movement from rest to work positions is more clearly shown in Fig. 3. Referring to this figure, it will be noted that pawl 19, under the influence of gravity, is moving out of the recess and further movement of the iron in the direction indicated permits the pendulum 12 to assume a vertical position and withdraw the rest arm.

As heretofore noted the end portion of the rest arm is inclined slightly upwardly from the horizontal and the inner peripheral edge of the combined guide and bearing member 24 is shaped to permit tangential engagement of the lower surface of the rest arm 21, during its movement transversely of the body of the iron. It will be readily appreciated that by means of this arrangement sidewise drift or floating of the rest arm will be restrained when it is in the retracted position, while the iron is at work.

In order to prevent button 23 from hammering or forcibly striking against cover member 4, when the iron is tilted to withdraw rest arm 21 to the retracted position, there is provided a stop arrangement comprising a screw 32, threadable into weight member 11 and maintained in the desired adjusted position by means of a lock nut 33.

It will be understood that the rest actuating mechanism can be operatively supported within

the iron housing, in a manner other than here shown, the type and arrangement of support depending upon the design of the particular flat iron with which the rest is to be used. For example, if there is sufficient space interiorly of the housing, the freely swingable pawl 19 and pendulum 12 can be supported from a bracket attached to the base of the iron. In the iron structure shown for purposes of illustration, the body portion 11 (Fig. 5), is cored or milled out to form a slot to accommodate the rest mechanism, the top of the weight 11 being recessed to receive the bracket or support plate 13, which is held in position within the recess by screws 31, or other suitable fastening means.

In accordance with the present invention, it will now be appreciated that I have provided an improved rest arrangement for pressing irons and the like, wherein the rest member, used to support the ironing surface above the underlying surface, is automatically extended to operative position or withdrawn to its normally retracted position, by merely tilting or rolling the iron in the desired direction. By means of the design of the arm actuating pendulum and associated pawl, together with the combined guide and bearing member for the rest arm, the device operates freely and easily with minimum effort on the part of the operator.

While I have shown and described the preferred embodiment of my invention, I wish it to be understood that I do not confine myself to the precise details of construction herein set forth, by way of illustrations as it is apparent that many changes and variations may be made therein, by those skilled in the art, without departing from the spirit of the invention, or exceeding the scope of the appended claims.

I claim:

1. In a pressing iron, including a body portion having an ironing surface, means to support the iron when not in use, with its ironing surface out of contact with the surface to be pressed, comprising a gravity actuated retractable rest member mounted interiorly of the body of the iron and adapted for sliding movement with respect thereto, said rest being normally seated in retracted position within the body of the iron and adapted to move outwardly therefrom when the iron is moved to rest position, and means to maintain the rest in iron supporting position.

2. In a pressing iron, including a body portion having an ironing surface, means to support the iron when not in use, with its ironing surface out of contact with the surface to be pressed, comprising a retractable rest member mounted interiorly of the iron and adapted for sliding movement transversely thereof, said rest being normally seated in the retracted position within the body of the iron and adapted to move outwardly therefrom under the influence of gravity when the iron is tilted to rest position, and means to maintain the rest in extended iron supporting position.

3. An improved rest for flat irons and the like, adapted to support an iron when not in use, with its ironing surface out of contact with the underlying surface, comprising a pendulum swingably supported within the body portion of the iron, an arm member having one end pivotally attached to the pendulum and adapted for sliding movement transversely of the body of the iron, said arm being normally seated in retracted position within the iron and adapted to move

outwardly therefrom under the influence of gravity when the iron is turned to rest position, and means to maintain the rest in extended iron supporting position.

- 5 4. An improved rest for flat irons and the like adapted to support an iron when not in use, with its ironing surface out of contact with the underlying surface, comprising a pendulum swingably supported within the body portion of the iron, an 10 arm member having one end pivotally attached to the pendulum and adapted for sliding movement transversely of the body of the iron, said arm being normally seated in retracted position within the iron and adapted to move outwardly therefrom under the influence of gravity when the iron is tilted to rest position, and means to maintain the rest in extended iron supporting position, comprising a pawl pivotally mounted interiorly of the iron in the vicinity of the pendulum, the free end of said pawl engaging with the pendulum and preventing inward movement thereof when the iron is in the rest position.
- 20 5. An improved rest for flat irons and the like, adapted to support an iron when not in use, with its ironing surface out of contact with the underlying surface, comprising a pendulum swingably supported within the body portion of the iron, said pendulum having a recess formed in its peripheral edge adapted to receive one end of 25 a pawl, an arm member having one end pivotally attached to the pendulum and adapted for a sliding movement transversely of the body of the iron, said arm being normally seated in retracted position within the iron and adapted to move outwardly therefrom under the influence of gravity when the iron is tilted to rest position, and means to maintain the rest in extended iron supporting position, comprising a pawl pivotally mounted interiorly of the iron in the vicinity 30 of the swingable pendulum, the free end of said pawl engaging with the recessed portion of the pendulum and preventing inward movement thereof when the iron is in the rest position.
- 35 6. In a pressing iron, including a body portion having an ironing surface, means to support the iron when not in use, with its ironing surface out of contact with the surface to be pressed, comprising a retractable rest having one end 40 thereof pivotally attached to a pendulum swingably supported interiorly of the iron and adapted for sliding movement transversely of the body of the iron, said rest being normally seated in the retracted position within the body of the iron and adapted to move outwardly therefrom under the influence of gravity when the iron is tilted to rest position and means to maintain the rest in extended iron supporting position.
- 45 7. In a pressing iron, including a body portion having an ironing surface, means to support the iron when not in use, with its ironing surface out of contact with the surface to be pressed, comprising a retractable rest having one end thereof 50 pivotally attached to a pendulum swingably supported interiorly of the iron and adapted for sliding movement transversely of the body of the iron, said rest being normally seated in the retracted position within the body of the iron and adapted to move outwardly therefrom under the influence of gravity when the iron is tilted to rest position and means to maintain the rest in extended iron supporting position.
- 55 8. In a pressing iron, including a body portion having an ironing surface, means to support the iron when not in use, with its ironing surface out of contact with the surface to be pressed, comprising a retractable rest having one end thereof 60 pivotally attached to a pendulum swingably supported interiorly of the iron, said rest being normally seated in the retracted position with its free end substantially flush with the exterior surface of the body of the iron and adapted to move outwardly therefrom under the influence of gravity when the iron is turned to rest position, and means to maintain the rest in extended iron supporting position comprising a pawl pivotally mounted interiorly of the body of the iron in the vicinity of the pendulum, the free end of said 65 pawl engaging with the pendulum and preventing 70 inward movement thereof when the iron is turned to rest position.
- 75 9. In a pressing iron, including a body portion having an ironing surface, means to support the iron when not in use, with its ironing surface out of contact with the surface to be pressed, comprising a retractable rest having one end thereof pivotally attached to a pendulum swingably supported interiorly of the iron, said rest being normally seated in the retracted position with its free end substantially flush with the exterior surface of the body of the iron and adapted to move outwardly therefrom under the influence of gravity when the iron is turned to rest position, and means to maintain the rest in extended iron supporting position comprising a pawl pivotally mounted interiorly of the body of the iron in the vicinity of the pendulum, the free end of said pawl engaging with the pendulum and preventing 80 inward movement thereof when the iron is turned to rest position.

inward movement thereof when the iron is in the rest position.

8. In a pressing iron, including a body portion having an ironing surface, means to support the iron when not in use, with its ironing surface out of contact with the surface to be pressed, comprising a retractable rest having one end thereof pivotally attached to a pendulum swingably supported interiorly of the iron, said pendulum having a recess formed in its peripheral edge adapted to receive one end of a pawl, the rest being normally seated in the retracted position with its free end substantially flush with the exterior surface of the body of the iron and adapted to move outwardly therefrom under the influence of gravity when the iron is turned to rest position, and means to maintain the rest in extended iron supporting position, comprising a pawl pivotally mounted interiorly of the body of the iron in the vicinity of the swingable pendulum, the free end of said pawl engaging with the recessed portion of the pendulum and preventing inward movement thereof when the iron is in the rest position.

9. In a flat iron, including a body portion having an ironing surface and a housing for the body portion, means to support the iron when not in use, with its ironing surface out of contact with the underlying surface, comprising a pendulum swingably supported interiorly of the housing, a retractable rest member having one end pivotally attached to the pendulum, the free end of said member extending through an opening in one side of the housing and having a foot member formed thereon, said rest being normally seated in the retracted position within the housing and adapted to move outwardly therefrom under the influence of gravity when the iron is turned to rest position, and means to maintain the rest in extended iron supporting position.

10. In a flat iron, including a body portion having an ironing surface and a housing for the body portion, means to support the iron when not in use, with its ironing surface out of contact with the underlying surface, comprising a pendulum swingably supported interiorly of the housing, a retractable rest member having one end pivotally attached to the pendulum, the free end of said member extending through an opening in one side of the housing and having a foot member formed thereon, said rest being normally seated in the retracted position within the housing and adapted to move outwardly therefrom under the influence of gravity when the iron is turned to rest position, and means to maintain the rest in extended iron supporting position comprising a pawl pivotally mounted interiorly of the housing in the vicinity of the swingable pendulum, the free end of said pawl engaging with the pendulum and preventing inward movement thereof when the iron is in the rest position.

11. In a flat iron, including a body portion having an ironing surface and a housing for the body portion, means to support the iron when not in use, with its ironing surface out of contact with the underlying surface, comprising a pendulum swingably supported interiorly of the housing, said pendulum having a recess formed in its peripheral edge adapted to receive one end of a pawl, a retractable rest member having one end pivotally attached to the pendulum, the free end of said member extending through an opening in one side of the housing and having a foot member formed thereon, said rest being normally seated in the retracted position within

the housing and adapted to move outwardly therefrom under the influence of gravity when the iron is turned to rest position, and means to maintain the rest in extended iron supporting position, comprising a pawl pivotally mounted interiorly of the housing in the vicinity of the swingable pendulum, the free end of said pawl engaging with the recessed portion of the pendulum and preventing inward movement thereof when the iron is in the rest position.

12. In a flat iron, including a body portion having an ironing surface and a housing for the body portion, means to support the iron when not in use, with its ironing surface out of contact with the underlying surface, comprising a pendulum swingably supported interiorly of the housing, a retractable rest member having one end pivotally attached to the pendulum, the free end of said member extending through an opening in one side of the housing and having a foot member formed thereon, a combined guide and bearing member for the retractable rest mounted interiorly of the iron housing adjacent the opening through which the free end of the rest projects, said rest being normally seated in the retracted position within the housing and adapted to move outwardly therefrom under the influence of gravity when the iron is turned to rest position, and means to maintain the rest in extended iron supporting position.

13. In a flat iron, including a body portion having an ironing surface and a housing for the body portion, means to support the iron when not in use, with its ironing surface out of contact with the underlying surface, comprising a pendulum swingably supported interiorly of the housing, said pendulum having a recess formed in its peripheral edge adapted to receive one end of a pawl, a retractable rest member having one end pivotally attached to the pendulum, the free end of said member extending through an opening in one side of the housing and having a foot member formed thereon, a combined guide and bearing member for the rest mounted interiorly of the iron housing adjacent the opening through which the free end of the rest projects, said rest being normally seated in the retracted position within the housing and adapted to move outwardly therefrom under the influence of gravity when the iron is turned to rest position, and means to maintain the rest in extended iron supporting position, comprising a pawl pivotally mounted interiorly of the housing in the vicinity of the swingable pendulum, the free end of said pawl engaging with the recessed portion of the pendulum and preventing inward movement thereof when the iron is in the rest position.

14. In a flat iron, including a body portion having an ironing surface and a housing for the body portion, means to support the iron when not in use, with its ironing surface out of contact with the underlying surface, comprising a pendulum swingably supported interiorly of the housing, a retractable rest member comprising a body portion having one end pivotally attached to the pendulum, the free end thereof extending through an opening in one side of the housing and having a foot member formed thereon, the end portion of the retractable rest in the vicinity of its free end being inclined upwardly with respect to the horizontal in retracted position, said rest being normally seated in the retracted position within the housing and adapted to move outwardly therefrom under the influence of gravity when the iron is turned to rest position, and

means to maintain the rest in extended iron supporting position.

15. In a flat iron, including a body portion having an ironing surface and a housing for the body portion, means to support the iron when not in use, with its ironing surface out of contact with the underlying surface, comprising a pendulum swingably supported interiorly of the housing, said pendulum having a recess formed in its peripheral edge adapted to receive one end of a pawl, a retractable rest member having one end pivotally attached to the pendulum, the free end of said member extending through an opening in the housing, the end portion of the retractable rest in the vicinity of its free end being inclined upwardly with respect to the horizontal in retracted position, a combined guide

and bearing member for the rest mounted interiorly of the iron housing adjacent the opening through which the free end of the rest projects, said rest being normally seated in the retracted position within the housing and adapted to move outwardly therefrom under the influence of gravity when the iron is tilted to rest position, and means to maintain the rest in extended iron supporting position, comprising a pawl pivotally mounted interiorly of the housing in the vicinity of the swingable pendulum, the free end of said pawl engaging with the recessed portion of the pendulum and preventing inward movement thereof when the iron is in the rest position.

THOMAS JEROME O'CONNOR.
